ALONZO LINTON BAUSMAN, OF SPRINGFIELD, MASSACHUSETTS

TIMING DEVICE FOR LAUNDRY MACHINES

Application filed November 23, 1929. Serial No. 409,369.

This invention relates to timing devices for presses, and will be described with particular reference to a timing device designed for a laundry press. One object of the invention is to provide a timing device which will be simple in construction and reliable in operation. Another object is to provide a timing device capable of ready and accurate adjustment. Another object is to provide a timing device having a double movement, an adjustable timed motion which is preferably entirely completed prior to the commencement of actuation of the mechanism controlled by the timer, and an unvarying motion not affected by the adjustment and serving to actuate the controlled mechanism.

In the particular adaptation shown, the timing device operates by mechanical contact with the control lever of a press operating valve. When contact has been established, it is desirable to move the valve as quickly as possible, and preferably always with a uniform rate. Before contact is established, the rate of movement of the timer can be varied without affecting the actuation of the control valve, and it is desirable for this reason to concentrate the variable element of the timing in this period.

The invention will now be described with reference to the accompanying drawings, in which:

Fig. 1 is a side elevation of a laundry press embodying my invention;

Fig. 2 is a diagrammatic representation of the main press operating motor, the timing device, and the necessary piping connections;

Fig. 3 is a sectional elevation, on an enlarged scale, of the timing device;

Fig. 4 is a diagram illustrating one stage of operation;

Fig. 5 is a similar diagram illustrating another stage of operation; and

Fig. 6 is a detail of a valve control.

The press upon which I have illustrated my invention is shown as mounted upon a frame 10 which directly supports a buck 11. The frame is also formed to carry a pivot 12, upon which a lever 13 oscillates. On the forward end of this lever is mounted the upper press head 14, which may be swung into either

the open position shown in full lines in Fig. 1 or the pressing position shown in dotted lines. At the rear end of the lever is pivoted at 15 a link 16, preferably having a turn-buckle 17 arranged intermediate its length to permit of adjustment. Pivoted at 18 to the lower end of link 16 is a second link 19, swinging at 20 upon the frame and forming a toggle with link 16 for the application of power to the press head. The press is arranged to be closed by power and opened by the action of a counterweight. A link 21 is pivoted at 15 to the lever 13 and at 23 to the counterweight 24 which is swung at 25 on the frame.

The driving power for closing the press is in the case shown derived from a pneumatic motor. A cylinder 26 is pivoted at 27 to the frame and carries a bar 28 sliding in a bearing 29 carried by the link 19. A piston rod 30 passes into the end of the cylinder opposite the pivot 27. At one end this rod is pivoted at 31 to the link 19 and at the other bears a piston 32 running in the cylinder 26. Surrounding the piston rod, and also passing through the end of the cylinder, is a sleeve 33 bearing a stop piston 34 within the cylinder and a travel limiting collar 35 outside it. The operation of these parts will be best understood after the piping connections to the cylinder have been considered.

A pipe 36 comes from any suitable source of compressed air, and is divided by a pressure reducing valve 37 from a low pressure line 38. In this low pressure line is a normally closed hand-operated valve 39 (preferably spring closed), and a generally similar but normally open hand-operated valve 40. A pipe 41 connects that portion of the low pressure line between the two valves with a passage in the cylinder pivot 27, a hole 42 joining this passage with the interior of the cylinder behind the piston 32. A pipe 43 joins the low pressure line, at a point beyond the normally open valve 40, with an intermediate port 44 in the cylinder. Beyond this port a small vent 45 is arranged to permit the escape of air entrapped between the pistons 32 and 34. A high pressure line 46 is connected with the main supply 36 and has a branch 47 leading to a four port valve 48. 10

This valve is provided with passages 49 and 50, a vent 51, and a pipe 52 leading to the end of the cylinder behind the piston 34. The valve is also preferably joined through a 5 check valve 53 to a combined high and low pressure line 54. When the valve 48 is in one position (shown in Fig. 2) the passage 49 joins the high pressure line 47 with the pipe 52, and the passage 50 is idle. In the other 10 position of the valve, the passage 49 joins the high pressure line 47 with the line 54, and the passage 50 joins the pipe 52 with the vent 51.

The main operating motor is shown in 15 Fig. 2 with the parts in the position they assume when the press is open. The press is arranged to be brought initially to a position in which the upper head is just short of pressing position. This motion is controlled by 20 the two valves 39 and 40, one being arranged for actuation by each hand of the operator. Both hands being necessarily engaged at a point remote from the press surfaces, all danger of the operator carelessly permitting 25 a hand to become caught by the press heads is removed. The function of valve 39 is of course to supply the cylinder with compressed air through pipe 41 and passage 42. Valve 40 has what may be termed a negative function. 30 Being normally open, it will, if not closed manually, permit the air from pipe 38 to pass into the cylinder through port 44, thus balancing out the effect of the air admitted through port 42 on the other side of 35 the piston. When both valves are actuated, air will enter the cylinder only through port 42 and piston 32 will be moved in a direction to close the press. This motion will continue until the piston 32 strikes piston 34, 40 which is held in its inner position by air under compression coming in through pipe 47, valve 48, and pipe 52. When it is desired to apply final heavy pressure to the press, the valve 48 is shifted to vent the space be- 45 tween piston 34 and pipe 52, and at the same time to introduce air from pipe 47 through the pipe 54 to port 44, past which the piston 32 had traveled at this period of the machine's operation. To return the press to inactive 50 position, a vent valve 55 is opened, either manually or by the timing device to be described, allowing the air to the rear of piston 32 to escape through ports 42 and 44, prefer- ably into a muffler 56. 55 The valve 48 is operated by a handle 57 (Figs. 1 and 6) located on the front of the machine and movable upwardly by hand to initiate the final heavy pressure. Valve 55 is operated by a handle 58 arranged so that 60 it cannot be moved downwardly to vent the cylinder without simultaneously moving the handle 57 down and therefore cutting off the supply of high pressure to the main cylinder and introducing it behind the piston 34. 65 This is conveniently accomplished by having

the handles 57 and 58 rotatable about aligned axes and forming the handle 58 as a hood overlying the handle 57 during its movement downwardly. The handle 58 has rigidly connected to it a lever 59 by which it, and therefore the handle 57 also, can be moved downwardly by the automatic timing mechanism about to be described. A spring 60 constantly urges the lever 59 and the handle 58 into the positions shown in Fig. 1 unless 75 the lever is raised by the timing device or the handle is manually depressed.

The timing device comprises a motive means, shown as a pneumatic cylinder 61, combined with a speed regulating means, 80 shown as a dash pot cylinder 62 containing a preferably viscous liquid such as oil. These two cylinders are conveniently arranged in axial alignment, and are separated by a partition wall 63. A piston rod 64 enters the cylinder 61, having at its end a contact member 65 for engagement with the lever 59, and carries within the cylinder a piston 66. The rod also extends through the wall 63, preferably through a stuffing box, and into the dash pot cylinder 62, carrying within this cylinder a piston 67. Instead of being solid, as piston 66 is, the dash pot piston conveniently is constructed to serve as a check valve permitting substantially unrestrained movement of the piston in one direction. For this purpose the piston has been shown as provided with holes closed by a clapper 68 when the piston moves to cause flow of the oil against the outer side of the clapper, and to 90 permit flow of the oil when the piston moves in the opposite direction. The clapper is limited in its movement away from the piston by a collar 69 secured to the rod 64.

Motion is imparted in one direction to 105 the piston 66, and consequently to the piston rod 64 and parts secured thereto, by compressed air under the control of a valve 70 (Fig. 2). This valve contains a passage 71, by means of which a pipe 72 joined to one 110 end of the cylinder 61 may be connected either to the supply line 46 or to a discharge pipe 73 leading to the muffler 56. To the handle 74 (Fig. 1) of this valve is pivoted a rod 75 passing through a hole in link 115 19 and bearing collars 76 and 77 which strike alternately against an abutment 78 on this link. The valve is thus opened automatically by the press when it reaches full pressing position and it is returned to its venting 120 position only after the press has opened.

The control of the timing device through its dash pot is arranged so that the contact member 65 will have a substantial passive travel before it strikes lever 59, and will then have a lever shifting motion during which it raises the lever from the full to the dotted line positions of Fig. 3. During this first or passive movement, the timing is done and the contact member is moved in general at 125 130

a lower speed than when it is actually engaged in shifting the lever 59. The preferred mechanism for accomplishing this result is a double by-pass system connected 5 with the dash pot. Three port pipes 79, 80 and 81 are joined to the cylinder 62, the holes in the cylinder wall being preferably multiple and small so as not to permit the piston packing to bulge into them. Pipes 79 and 80 are at the ends of the cylinder while pipe 81 is at an intermediate point separated from pipe 80 a distance slightly more than enough to completely shift the lever 59. Pipes 80 and 81 are connected by a by-pass pipe 82, while pipes 79 and 81 are connected by a by-pass pipe 83 having in it a valve 84 conveniently of the needle valve type and serving to restrict the flow of liquid through the pipe 83 to any desired extent.

During the first or passive part of travel of the piston rod, before the contact member 65 has struck lever 59, the operation of the parts is as shown in Fig. 4, the dash pot liquid flowing through the by-pass system 81, 83, 79. The speed with which the liquid can flow, and consequently the speed of the piston rod, can be controlled as desired by the valve 84. The by-pass system 80, 82, 81 is now inactive as both of its ports are on 30 one side of the piston. When the piston passes pipe 81, a different operation results. The by-pass system 81, 83, 79 has become inactive, as both ports are on the same side of the piston, but the system 80, 82, 81 has 35 become operative (Fig. 5). There being no restriction in this latter system, a greater speed of the piston rod is permitted, and this speed will not be affected by any variation in the setting of the valve 84. It will be seen 40 that the arrangement described will always give a rapid and positive action in shifting the control lever 59, while the slower passive part of the movement can be varied in time as desired without changing the duration or speed of the lever-shifting portion of 45 the movement. The contact member 65 will be kept elevated until the valve 70 is again turned by the action of collar 76 to vent the cylinder 61, when it will be pulled downwardly to its inactive position by suitable 50 springs 85. During this downward movement, the clapper 68 will rise and permit the oil within cylinder 62 to flow upwardly through the holes in the piston 67, thus adding 55 their check valve action to the by-passing action of the piping systems to permit a comparatively rapid descent of the contact member and a consequent rise of valve lever 58 under the influence of spring 60.

60 What I claim is:

1. In a laundry press having opposed relatively movable pressing members and power means for operating them, a manual control operative to cause motion of the press to inactive position, and automatic means for

causing motion of the manual control a predetermined time after closing of the press, comprising a contact device having a control shifting movement and a preliminary timing movement, and means for varying the duration of the timing movement without varying the duration of the control shifting movement. 70

2. A laundry press comprising coacting press members movable towards and from each other, power means for exerting pressure between the members, a control member operable to cause release of the pressure between the members, a device having a lost motion connection with said control member for operating it, means automatically actuated at the closing of the press members for initiating the operation of said device, and retarding means operable during said period of lost motion only to vary the length of time the press members are maintained under pressure. 75

3. A laundry press comprising coacting press members movable towards and from each other, power means for exerting pressure between the members, a control member operable to cause release of the pressure between the members, a device having a lost motion connection with said control member for operating it, means automatically actuated at the closing of the press members for initiating the operation of said device, a dash pot connected to said device to retard its operation in a control-operating direction, and comprising a cylinder and piston, a restricted by-pass joining one end of the cylinder with an intermediate point thereof to control the motion of the piston during the portion of its stroke corresponding to the lost motion travel of said device, and a second substantially unrestricted by-pass joining the other end of the cylinder with said intermediate point to permit quick motion of said device during its actuation of the control member. 90

4. A laundry press comprising coacting press members movable toward and from each other, power means for exerting pressure between the members, a control member operable to cause release of the pressure between the members, a pneumatic cylinder, a piston running therein and having a lost motion connection with the control member, a valve for admitting compressed air to the cylinder, mechanism actuated automatically upon the closing of the press members for opening the valve, and retarding means operable during the lost motion part of the stroke of the piston only to exert a timing action. 105

In testimony whereof I have affixed my signature.

ALONZO LINTON BAUSMAN.
